Primary Examiner — Catherine S Posthauer*Assistant Examiner* — Katherine E Morris(74) Attorney, Agent, or Firm — Leason Ellis LLP(57) CLAIM

The ornamental design for a bottle, as shown and described.

DESCRIPTION

FIG. 1 is a front and right side view of a bottle showing a first embodiment of my new ornamental design;

FIG. 2 is a front view thereof;

FIG. 3 is a rear view thereof;

FIG. 4 is a right side view thereof;

FIG. 5 is a left side view thereof;

FIG. 6 is a top plan view; and

FIG. 7 is a bottom plan view thereof;

FIG. 8 is a front and right side view of a bottle showing a second embodiment of my new ornamental design;

FIG. 9 is a front view thereof;

FIG. 10 is a rear view thereof;

FIG. 11 is a right side view thereof;

FIG. 12 is a left side view thereof;

FIG. 13 is a top plan view; and,

FIG. 14 is a bottom plan view thereof.

The broken lines shown in the drawings depict portions of the bottle that form no part of the claimed design.
